(57) **CLAIM**

The ornamental design for a perforated cooking pan, as shown and described.

DESCRIPTION

FIG. 1 is an isometric view of a perforated cooking pan showing our new design.

FIG. 2 is a top view thereof.

FIG. 3 is a bottom view thereof.

FIG. 4 is a side view thereof with both sides being substantially identical.

FIG. 5 is an enlarged front view thereof; and,

FIG. 6 is an enlarged rear view thereof.

The broken lines shown in the drawings are for illustrative purposes only and form no part of the claimed design.
